UNITED STATES PATENT OFFICE.

JOHN P. KELLY, OF PITTSFIELD, MASSACHUSETTS.

LUBRICATOR FOR AIR-COMPRESSORS.

1,312,330.

Specification of Letters Patent.

Patented Aug. 5, 1919.

Application filed January 20, 1919. Serial No. 272,004.

To all whom it may concern:

Be it known that I, JOHN P. KELLY, a citizen of the United States, and a resident of Pittsfield, in the county of Berkshire and 5 State of Massachusetts, have invented a certain new and useful Improvement in Lubricators for Air-Compressors, of which improvement the following is a specification.

This invention relates to lubricators, and 10 more particularly to lubricators for air pump cylinders.

In devices of this character, as heretofore used, difficulty has been experienced in obtaining a uniformity in the feed of oil under 15 the varying conditions in actual service, due principally to the great changes in temperature to which the oil is subjected. The object of my invention is to obtain a more uniform and certain feed of the oil through 20 the feed passages to the pump cylinders, and for this purpose I provide means for agitating the oil and maintaining the same in a thin fluid condition, regardless of variations in temperature and other conditions. 25 Another feature of my improvement comprises reciprocating means operating in the feed passage for controlling the feed of the oil, and according to another feature of my invention, the agitating means and reciprocating means are operated automatically by the action of the pump.

In the accompanying drawing: Figure 1 is a vertical central section of one form of lubricator embodying my improvement; 35 Fig. 2 a plan of the propeller wheel, for rotating the shaft of the agitating mechanism; Fig. 3 an inverted horizontal section of said shaft taken on the line 3—3 of Fig. 1; and, Fig. 4, a horizontal section taken in the 40 same plane.

According to the construction shown, the lubricator comprises a casing, 5, having a chamber, 6, for containing oil, and provided with a cap, 7, having perforations, 8, 45 through which air may be drawn by the suction action of the pump. From the bottom of the oil chamber a feed passage leads downward into a conduit, 9, containing a check valve, 10, normally held closed by a spring, 11, located in a chamber, 12, from 50 which the outlet passage, 13, for the oil leads through the base of the casing, which is threaded at 14, for connection with the air cylinder of the pump. While any suitable 55 form of check valve may be employed, the

valve, 10, is shown as provided with a tubular guide stem, 24, extending within the feed passage, 9, and having perforations, 25, for the passage of air and oil when the valve is opened by the suction action of the pump 60 piston.

For the purpose of maintaining the oil in the chamber in a thin fluid condition under variations in temperature, so as to preserve a constant and uniform feed, I provide 65 means for agitating and heating up the oil in the chamber. While any suitable form of agitating mechanism operated by the action of the pump may be employed, a preferred construction comprises a spindle, 15, having 70 projecting arms, 16, below the level of the oil in the chamber, and a fan wheel or propeller, 17, located in close proximity to the air inlet ports, 8. An air passage is also provided from the space within the chamber above the level of the oil to the feed passage or conduit, 9, and this passage, 18, is preferably formed by making the spindle, 15, hollow, said passage including the radiating passages, 19, formed in the disk, 20, 75 near the upper end of the spindle, 15. The spindle is supported by means of a collar, 22, having a face bearing upon a seat, 21, formed upon the casing at the bottom of the oil chamber. The hollow spindle, 15, preferably extends through the feed passage 80 into the outlet conduit, 9, with a more or less loose bearing fit, and for the purpose of causing a reciprocating movement of said spindle in the feed passage, the engaging 85 faces of the seat, 21, and the collar, 22, may be made undulating or formed upon a sort of a sinuous curve, as indicated, whereby when the spindle is rotated, it will also be reciprocated vertically as the high and low 90 portions of the curved surface on the collar pass over the corresponding curved portions of the seat. This produces a plunger action 95 for the oil in passing through the feed passage. The upper end of the spindle may be provided with a suitable bearing in the cap portion, 7. Oil may be introduced into the chamber, 6, through a suitable filling plug, 26.

The operation is as follows: During the 105 suction stroke of the pump piston the partial vacuum produced in passage, 13, effects the opening of valve, 10, against its spring, 11, and air is drawn in through inlet ports, 8, in the cap to the chamber, 6, above the oil, 110

and from thence through passages, 19, in disk 20, passage, 18, in the spindle, 15, feed passage and conduit, 9, hollow stem, 24, ports, 25, chamber, 12, and passage, 13, to the pump cylinder. The current of air taking up and carrying with it the small amount of oil in the feed passage.

The induced streams of air entering the ports, 8, impinge upon the blades of the fan wheel or propeller, 17, and cause the same to rotate rapidly together with the spindle, 15, disk, 20, collar, 22, and agitating arms, 16. This rapid rotation of the arms, 16, in the oil at the bottom of the chamber, 15, serves to so agitate and beat up the oil that it is maintained in a thin fluid state adapted for feeding uniformly even when subjected to low degrees of temperature. As the spindle is rotated it also moves up and down through the inlet portion of the feed passage for the oil, and by this reciprocating movement produces a sort of plunger action upon the oil to assist in feeding the same through the restricted passage around the outer surface of the spindle. In this manner the oil is fed slowly and constantly in a thin film down through the passage into conduit, 9, where it is taken up by the incoming air through passage, 18, and carried into the pump cylinder. This produces a slow and uniform rate of feed to the oil even under varying conditions and temperature.

At each compression stroke of the pump piston, the pressure acting through passage, 13, instantly closes the valve, 10, assisted by the spring, 11, and prevents the compressed air from blowing out through the lubricator.

As the air inlet passage, 18, communicates with the feed conduit, 9, at a point below the restricted feed passage from the oil chamber around the lower end of the spindle, it will be seen that oil in the chamber is relieved from the suction action of the pump and remains substantially balanced as to air pressure. This prevents the oil from feeding too rapidly. The closeness of the fit between the lower end of the spindle and the walls of the feed passage may be made to suit the desired conditions.

With the form of check valve shown, having the tubular guide stem, 24, fitting within the feed passage, 9, and the perforations, 25, at the face of the valve, it will be seen that the capacity of the passage for the flow of air may be determined by the number and size of the perforations, and by varying the capacity of the passage through said perforations relative to the capacity of the passage, 18, through the spindle, the suction effect upon the oil through the feed passage around the end of the spindle may be varied to give the desired amount of feed.

My improved construction also has the advantage of being simple and compact, easily taken apart for cleaning by simply remov-

ing the cap, 7, and lifting out all of the movable parts together, and readily assembled in position.

Having now described my invention, what I claim as new and desire to secure by Letters Patent is:

1. In a lubricator for air pumps, the combination of a casing having an oil chamber, a feed passage leading therefrom, and agitating mechanism in said chamber, said mechanism being operated by the action of the pump for agitating the oil.

2. In a lubricator for air pumps, the combination of a casing having an oil chamber, a feed passage leading therefrom, agitating mechanism in said chamber, and means actuated by the suction of the pump for operating the agitating mechanism.

3. In a lubricator for air pumps, the combination of a casing having an oil chamber, a feed passage leading therefrom, a rotatable agitator in said chamber, a passage for admitting air to said feed passage, and means actuated by the air drawn into said passage by the suction of the pump for operating the agitator.

4. In a lubricator for air pumps, the combination of a casing having an oil chamber, a feed passage leading therefrom, a rotatable shaft having projecting arms in said chamber, and a propeller wheel mounted on said shaft and operated by the suction of the air pump.

5. In a lubricator for air pumps, the combination of a casing having an oil chamber, a feed passage leading therefrom, a hollow spindle provided with projecting arms and a propeller wheel, the passage in said spindle communicating with the feed passage and with the air space in said oil chamber, and air inlet ports adjacent to the propeller wheel.

6. In a lubricator for air pumps, the combination of a casing having an oil chamber, a feed passage leading therefrom, a check valve in said feed passage, and agitating means located in said oil chamber, both the agitating means and the check valve being operated by the suction of the air pump.

7. In a lubricator for air pumps, the combination of a casing having an oil chamber, a feed passage leading therefrom, a spindle extending into the feed passage, and means operated by the action of the air pump for reciprocating said spindle.

8. In a lubricator for air pumps, the combination of a casing having an oil chamber, a feed passage leading therefrom, a passage for admitting air into said feed passage, a spindle extending from the oil chamber into the feed passage, and means operated by the suction of the air pump for reciprocating said spindle.

9. In a lubricator for air pumps, the combination of a casing having an oil chamber,

a feed passage leading therefrom, a spindle extending from said chamber into the feed passage and having projecting arms, and means operated by the suction of the air pump for rotating and reciprocating said spindle.

10. In a lubricator for air pumps, the combination of a casing having an oil chamber, a feed passage leading therefrom, a spindle extending from the oil chamber into the feed passage and provided with projecting arms and a propeller wheel, air inlet ports adjacent to said wheel, and means operated by the rotation of the spindle for reciprocating the same.

11. In a lubricator for air pumps, the combination of a casing having an oil chamber, a feed passage leading therefrom, a rotatable spindle extending from the oil chamber into the feed passage and having projecting arms, a propeller wheel and a disk on the upper portion of said spindle, and an

air inlet passage extending through said disk and said spindle to the feed passage.

12. In a lubricator for air pumps, the combination of a casing having an oil chamber, a feed passage leading therefrom, a spindle extending from the oil chamber into the feed passage and provided with a collar having a curved bearing surface, a supporting seat therefor having a corresponding curved surface, and means for rotating said spindle.

13. In a lubricator for air pumps, the combination of a casing having an oil chamber, a feed passage leading therefrom, a check valve having a tubular guide stem mounted with a sliding fit in said feed passage, and perforations in said tubular stem at the face of the valve, and an air inlet passage communicating with the feed passage.

In testimony whereof I have hereunto set my hand.

JOHN P. KELLY.
